UNITED STATES PATENT OFFICE

SHIRLEY S. FRENCH, OF CANTON, OHIO, ASSIGNOR, BY MESNE ASSIGNMENTS, TO THE
BERGER MANUFACTURING COMPANY, A CORPORATION OF NEW JERSEY

LOCKER LATCH

Original application filed May 26, 1928, Serial No. 280,847. Divided and this application filed August 24, 1929. Serial No. 388,098.

This invention has for its object the provision of a latching mechanism for a locker which will be simple in operation, of sturdy construction, permit of easy assembly, and 5 present withal a neat and attractive appearance.

Another object of the invention is to provide a door for a locker having a novel tubular formation at the edge thereof, which 10 functions not only to reinforce the door, but at the same time, serves to enclose and conceal a latching bar, and to conceal the connection between the latching bar and the door handle which is adapted to be directly connected thereto.

This application is a division of my co-pending application filed May 26, 1928, Serial No. 280,847, entitled "Locker latch".

In the patent to Sturm and Caldwell, No. 20 1,671,328, there is described a latching mechanism for a locker in which a latching bar is enclosed in a tubular housing or reinforcement at the edge of the door, the bar being positively forced into latching position 25 by means of especially designed hooks or keepers which enter the housing and engage slots in the latching bar. A handle is secured directly to the latching bar, and this handle serves to support the bar in operative 30 position in the housing when the door is open. This construction has the disadvantage, that should the handle become accidentally disengaged from the bar, the bar drops out of the housing, and is likely to be injured, and it is also necessary to reassemble 35 the bar and handle before the door can be closed.

In accordance with the present invention, the bar is provided with novel means which 40 enable it to be positively moved into latching position when the door is closed, in the same manner as the latching bar described in the aforesaid patent of Sturm and Caldwell, and in addition, these means serve to 45 support the bar in operative position in the housing when the door is ajar or open, regardless of whether or not the handle is secured thereto.

These and other objects of the invention 50 will become more readily apparent in the

course of the following description of one embodiment of the invention, taken in connection with the accompanying drawings, wherein

Fig. 1 is a front elevation of a locker in 55 which is embodied the novel features of the present invention;

Fig. 2 is a cross-section through the tubular reinforcement and the latching bar, taken on the line 2-2 of Fig. 1;

Fig. 3 is a cross-section through the door and adjacent portions of the locker, taken on the line 3-3 of Fig. 1;

Fig. 4 is an exploded view of a portion of the tubular reinforcement, a portion of the latching bar, and a portion of the door frame, showing the relation of these parts to each other, and 65

Fig. 5 is a detail view of one of the latching pins. 70

Referring more particularly to the drawings, the locker includes a sheet-metal door frame 1, and a door 2 hinged thereon. The door 2 is formed at one of its side edges with a tubular housing or reinforcement consisting of two spaced box-flanges 3 and 4, each of which includes inner legs 5 and outer legs 6, and an intervening connecting web 7, spaced from the rear face of the door. The box flanges and intervening connecting web 75 thus enclose a space of channel cross-section. The leg 6 of the box-flange 3 may be spot welded or otherwise secured to the rear face of the door, as clearly shown in Fig. 3. Vertically spaced slots 8 are provided in the door, adjacent the connecting web 7. The tubular housing is closed at the top by a flange 9, and is left open at the bottom to facilitate insertion and removal of a latching bar 10. 80

The latching bar 10 is of channel cross-section having a web 11, and spaced flanges 12 and 13, terminating in spacing flanges 14. The web 11 is provided with vertically spaced slots 15 for the reception of the tenons 16 of a handle 17, and has secured thereto, a flat 85 retaining spring 18, which serves a purpose to be presently disclosed. The flanges 12 and 13 of the latching bar are provided respectively with vertically spaced sets of holes 19 and 20, which serve to receive latching pins 90

21 and other pins 22 which serve a purpose to be presently described. The inner legs 5 of the box-flanges 3 and 4 are provided with elongated slots 23 in which the pins 21 and 22 slide when the latching bar is in operative position (see Fig. 2). The outer leg 6 of box-flange 3 is provided with spaced holes 24 through which the pins 21 and 22 are entered when the various parts of the latching mechanism are assembled.

10 The pins 21 and 22 are slotted longitudinally as at 25, to provide the beveled prong ends 26, which are united to the body portion of each pin by means of a neck portion 27 of reduced diameter.

15 The latching mechanism also includes hooks or keepers 28, mounted on the door frame 1. Each of these keepers is formed with an upwardly sloping edge 29, a downwardly sloping edge 30 of considerably greater length than the edge 29, and a seat 31.

20 The latching mechanism and the handle are assembled on the door in the following manner:

25 The latching bar 10 is inserted through the opening at the bottom of the tubular housing, and pushed up into the housing, until the slots 15 in the web of the bar are opposite the slots 8 in the door. The tenons 16 of the 30 handle 17 are then caused to enter the slots 8 and 15, and the latching bar is then permitted to drop to the position shown in Fig. 2, the web of the bar engaging behind the tenons. The upper end of the spring 18, in this position, substantially abuts the lower 35 end of the upper tenon 16, and the latching bar is thereby securely held in operative position.

40 The pins 21 and 22 are then entered through the holes 24, and into the slots 23, and holes 19 and 20, so that they occupy the position shown in Fig. 3. The holes 20 are slightly smaller in diameter than the holes 19, and the beveled prong ends 26 of the pins are slightly compressed when they enter these 45 holes. When the prong ends of the pins have passed through the holes 20, the compression is relieved, and the pins are securely retained in place. In the present embodiment of the invention, three latching pins are employed, but their number may be varied without departing from the scope of the invention.

50 It will be apparent from a consideration of Figs. 2, 3, and 4, that when the door is closed, the pins 21 will ride up over the upwardly sloping edges 29 of the keepers 28 until the uppermost point of these edges is reached. The pins 22 will then begin to contact with 55 the downwardly sloping edges 30 of the keepers, and the pins 21 will be positively forced to move down into the seats 31. In this manner, the locker door is effectively shut or latched regardless of how small or great a force is used to effect the latching.

60 It will also be noted that the pins 22 in their lowermost position, as shown in Fig. 2, abut the lower ends of the slots 23 in the legs 5 of the box-flanges 3 and 4, and thereby prevent the latching bar from falling out of the 65 housing in the event that the handle should become disengaged from the bar.

Claims:

1. Latching mechanism for a locker comprising a bar of channel cross-section, latching pins extending through the flanges of said bar, and keepers for attachment to the body of the locker and adapted for interlocking engagement with said pins.

70 75 80 85 90 95 100 105 110 115 120 125 130

2. Latching mechanism for a locker comprising a bar of channel cross-section, latching pins extending through the flanges of said bar, keepers for attachment to the body of the locker, and other pins extending through the flanges of said bar, said last-named pins coacting with said keepers to positively force the latching pins into interlocking engagement with the keepers when the locker door is closed.

3. A latching bar for a locker comprising a member of channel cross-section, and latching pins extending through the flanges of the bar.

90 95 100 105 110 115 120 125 130

4. A latching bar for a locker having a body provided with keepers comprising a member of channel cross-section, latching pins extending through the flanges of the bar and adapted for interlocking engagement with the keepers on the locker body and other pins extending through the flanges of the bar and adapted to coact with the keepers to positively force the latching pins into interlocking engagement with said keepers.

In testimony whereof I affix my signature.

SHIRLEY S. FRENCH.
